UNITED STATES PATENT OFFICE.

ROBERT B. LIDDELL, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

DESIGN FOR A PEDESTAL FOR CAR-SEATS.

43,460.

Specification for Design.

Patented Jan. 21, 1913.

Application filed September 23, 1911. Serial No. 651,004. Term of patent 14 years.

To all whom it may concern:

Be it known that I, ROBERT B. LIDDELL, a citizen of the United States, residing in Philadelphia, Pennsylvania, have invented a certain new, original, and ornamental Design for a Pedestal for Car-Seats, of which the following is a specification, reference being had to the accompanying drawing, forming part thereof.

The figure is a perspective view of a pedestal for car seats illustrating my design.

I claim:—

The ornamental design for a pedestal for car seats, as shown.

ROBERT B. LIDDELL.
